(57) **CLAIM**

The ornamental design for an insertion assisting tool for endoscope as shown and described.

DESCRIPTION

FIG. 1 is a perspective view of an insertion assisting tool for endoscope showing of my new design;

FIG. 2 is an enlarged partial perspective view of proximal end portion of the insertion assisting tool for endoscope;

FIG. 3 is a front view of the insertion assisting tool for endoscope;

FIG. 4 is a rear view thereof;

FIG. 5 is a top plan view thereof;

FIG. 6 is a bottom plan view thereof;

FIG. 7 is a right side view thereof;

FIG. 8 is a left side view thereof;

FIG. 9 is an enlarged partial view of 9-9 section of FIG. 3;

FIG. 10 is an enlarged partial view of 10-10 section of FIG. 4;

FIG. 11 is an enlarged partial view of 11-11 section of FIG. 5;

FIG. 12 is an enlarged partial view of 12-12 section of FIG. 6;

FIG. 13 is a view which is viewed from 13-13 section of FIG. 9; and,

FIG. 14 is a view which is viewed from 14-14 section of FIG. 9.

The broken lines illustrate portions of the insertion assisting tool for endoscope and form no part of the claimed design. A line indicated by alternate long and short dashed lines is used only for indicating boundary of the enlarged partial views.

1 Claim, 10 Drawing Sheets
